UNITED STATES PATENT OFFICE.

WILLIAM W. MACFARLANE, OF ELKINS PARK, PENNSYLVANIA.

TRAIN-CONTROL SYSTEM.

1,363,525.

Specification of Letters Patent. Patented Dec. 28, 1920.

Application filed March 19, 1919. Serial No. 283,595.

To all whom it may concern:

Be it known that I, WILLIAM W. MACFARLANE, a citizen of the United States, and a resident of Elkins Park, in the county of 5 Montgomery and State of Pennsylvania, have invented certain new and useful Improvements in Train-Control Systems, of which the following is a specification.

The present invention relates generally to 10 train control system and has more particularly reference to means for preventing so-called overbleeding of the train pipe, that being an object of the invention.

In the accompanying drawing the invention 15 is disclosed in a concrete and preferred form in which—

Figure 1 is a diagrammatic view of a system embodying the invention with parts shown in section.

20 Fig. 2 is a vertical sectional view in line 2—2 through the piston rod shown in Fig. 1.

Fig. 3 is a detail view of the fluid pressure system controlled circuit breaker.

A fluid pressure brake system is indicated 25 by the train pipe 1 associated with which is a brake valve 2 normally in an inoperative position to hold pipe 1 closed and which when opened serves to reduce pressure in said pipe. The means for actuating the 30 brake valve may vary widely, but in the present instance take the following form: 3 is a cylinder divided by means of partition 4 into a lower and an upper compartment respectively indicated at 5 and 6. 7 is 35 a piston rod extending through a stuffing box in partition 4 and projecting out through the upper end of cylinder 3 to a point adjacent to actuating lever 8 of the brake valve. Carried by rod 7 are two pis-

40 tons 9 and 10, the former at the lower end of compartment 5 and the latter at the lower end of compartment 6 when the parts are in their normal position, a spring 11 acting to urge the parts into such position. To per-

45 mit air to escape from one side of piston 10 to the other, a bypass 12 is provided; and

an orifice 13 is provided near the top of the

lower compartment to allow piston 9 to rise

without compressing the air within said

50 lower compartment. A pipe 14 extends from the train pipe to a casing 15, and a pipe 16 connects said casing with the lower end of lower compartment 5. Casing 15 has a valve 17 at its upper end and another

55 valve 18 at its lower end, said valves being connected by valve stem 19 and being so ar-

ranged that when valve 17 is closed valve 18 is open and vice versa.

20 is an electro-magnetic device here shown as a solenoid the core of which is 60 connected to a lever 21 pivoted at 22 in a stationary bearing 23, said lever 21 engaging with one end of a second lever 24 also pivoted on 23 whose other end engages lower end of valve stem 19. It will be seen that 65 so long as magnet 20 is energized, valve 17 is closed and 18 is open. Consequently, no air can pass from train pipe 1 to lower compartment 5 and spring 11 is therefore effective to hold pistons 9 and 10 in their 70 lowermost position and brake valve 2 will be closed or inoperative and no reduction in the train pipe will take place. If, however, 20 is deenergized, valve 18 will close and 17 will open thereby permitting air to pass 75 train pipe 1 to lower compartment 5 beneath piston 9. As the air must overcome the action of spring 11, upward movement of piston 9 and piston rod 7 will be retarded, but, when sufficient pressure has been built 80 up beneath piston 9, piston rod 7 will rise and will open brake valve 2 by raising actuating means 8. The reason for delaying the action of the device is to admit of momentary deenergization of magnet 20 without 85 operating brake valve 2. When magnet 20 is reenergized, valve 17 will be closed and valve 18 will be opened, the action of spring 11 restoring the parts to their original position and the air beneath piston 9 escaping 90 past valve 18.

Magnet 20 is included in a circuit consisting of conductors 25, 26 and 27 and battery 28. This circuit is normally held closed by circuit breaker 29 which is an 95 armature controlled by relay 30, and the latter may have its own circuit under control of coil 31 which is a device responsive to changes in traffic conditions. The details of device 31 need not be described since it 100 forms no part of the present invention. Suffice it to say, that so long as traffic conditions are safe, the circuit energizing magnet 20 will remain closed and brake valve 2 will be inoperative; but when traffic conditions change to denote caution or danger, 105 relay 30 will be deenergized, thereby rupturing the circuit including magnet 20 and rendering brake valve 2 operative to cause reduction in pressure in pipe 1. To prevent overbleeding of pipe 1, provision is 110 made whereby when a certain reduction in

pressure has been effected, magnet 20 will be energized regardless of traffic conditions or regardless of position of circuit breaker 29, said magnet being again deenergized 5 when pressure has again been built up above a given minimum. The means for effecting this, take, in the present instance, the following form: A pressure gage 32 is interposed in pipe 14 and its registering hand 33 is utilized as a movable contact member and electrically connected by means of conductor 34 to conductor 26. An adjustable stop or contact member 35 is properly insulated from hand 33 and is connected by 10 conductor 36 to conductor 27. If contact 35 is set, say at 12½ lbs. pressure indicating position, then when magnet 20 is deenergized by a change in traffic conditions a reduction in pressure of pipe 1 will be effected, 15 this reduction continuing until movable contact 33 encounters contact 35 when a circuit is closed through battery 28 and magnet 20 thereby closing brake valve 2. As soon as pressure is built up again, 20 contact 33 will move away from contact 35 and magnet 20 will be deenergized assuming that relay 30 is still deenergized; but if traffic conditions have meanwhile changed and armature 29 has been picked up then 25 pressure will continue to be built up until the usual maximum employed in existing devices has been attained.

I claim:

1. Train control means comprising: a fluid 35 pressure brake system, a brake valve included in said system for reducing pressure therein, electro-magnetic means which when energized holds the brake valve inoperative, a normally closed circuit normally energizing the electro-magnetic means, means for rupturing the closed circuit, and means for automatically closing the circuit to re- 40 energize the electro-magnetic means when a predetermined reduction in the fluid pressure system has been effected.

2. Train control means comprising: a fluid pressure brake system, a brake valve included in said system for reducing pres-

sure therein, electro-magnetic means which when energized holds the brake valve inoperative, a normally closed circuit normally energizing the electro-magnetic means, means for rupturing the closed circuit at one point, and means for automatically closing the circuit at another point to 55 reenergize the electro-magnetic means when a predetermined reduction in the fluid pressure system has been effected.

3. Train control means comprising: a fluid pressure brake system, a brake valve 60 included in said system for reducing pressure therein, a normally closed circuit normally holding the brake valve inoperative, traffic controlled means for rupturing said circuit, and fluid pressure controlled means 65 for closing the circuit when the pressure in the brake system drops below a certain point.

4. Train control means comprising: a fluid 70 pressure brake system, a brake valve included in said system for reducing pressure therein, a normally closed circuit normally holding the brake valve inoperative, a traffic controlled circuit breaker in said circuit, and a circuit breaker controlled by fluctuation 75 of pressure in the fluid pressure brake system also included in said circuit.

5. Train control means comprising: a fluid pressure brake system, a brake valve included in said system for reducing pres- 80 sure therein, a normally closed circuit normally holding the brake valve inoperative, a circuit breaker holding the circuit open at one point so long as a given minimum of pressure exists in the brake system and 85 closing said circuit upon a decrease in pressure below the given minimum, and a circuit breaker for opening and closing the circuit at another point in accordance with traffic conditions, the circuit being complete when either circuit breaker is in its closed position.

Signed at Philadelphia, in the county of Philadelphia and State of Pennsylvania, this 6th day of March, 1919.

WILLIAM W. MACFARLANE.
